UNITED STATES PATENT OFFICE.

EDWARD A. RIX, OF SAN FRANCISCO, CALIFORNIA.

PNEUMATIC PUMPING-ENGINE.

SPECIFICATION forming part of Letters Patent No. 605,187, dated June 7, 1898.

Application filed July 16, 1897. Serial No. 644,812. (No model.)

To all whom it may concern:

Be it known that I, EDWARD A. RIX, a citizen of the United States, and a resident of the city and county of San Francisco, State of California, have invented certain new and useful Improvements in Pneumatic Pumping-Engines, of which the following is a specification.

My invention relates to a motive-engine impelled by compressed air, wherein the degree or range of expansion lowers the temperature of the exhausted air below the freezing-point of water, impeding or obstructing motion unless the air be heated, and especially to pneumatic engines of the compound type employed for pumping water.

My improvement consists in employing water pumped by the engine as a means of interheating the air on its passage from the first to the second or from the high to the low pressure cylinder and in apparatus therefor.

The object of my invention is to provide a simple and inexpensive means of reheating or interheating the air between the stages of its expansion in compound engines, and thus augmenting its volume and effect and avoiding congelation of moisture or entrained water in the air at the point of final release. To this end I provide apparatus as shown in the accompanying drawing, which illustrates diagrammatically the application of my invention to a compound pneumatic engine.

I am aware that it is common to cool air between stages of its compression and to heat it before and during its application and expansion; but the heat thus applied is derived from some extraneous source—from fire or steam, for example, in either case causing an expense in proportion to the heat supplied or consumed. In my invention this added heat is derived from water pumped by the compressed air and under circumstances where the heat extracted from the water causes no loss or expense and may even be desirable by lowering the temperature of the water used.

In the application of compressed air for motive purposes, beginning in the first or high-pressure cylinder at a temperature of 60° and, for example, at a pressure of ninety pounds per inch and expanding to a pressure of thirty-five pounds per inch, a temperature of minus 30° is produced. This air if further expanded

in a second or low-pressure cylinder produces freezing and obstruction. If, however, this air after expansion in the first cylinder is exposed to a sufficient volume of water with a temperature of 60°, the difference in temperature being 90°, convection is rapid, raising the temperature of the air to that of the water, or approximately so, depending on the volume of water and the time and intimacy of contact or exposure. If the air thus warmed is applied in a second cylinder and expanded to the atmospheric pressure, the final temperature will be such that no difficulty will be experienced by congelation.

It is evident that the higher the temperature of the reheating-water the more economical will be the process of pumping, and at a high temperature the gain from this source will materially assist motive power.

In the case of pumping-engines for use in mines, where my invention is especially applicable because it is difficult and dangerous to heat by fire or steam, the temperature of the water is usually higher than 60°, and in deep mines, where pneumatic engines are especially required for pumping, the water is usually much warmer and effective in proportion for interheating the impelling-air.

Referring to the drawing, 1 is a pumping-engine of the common type, provided with cylinders 2 and 3 and arranged to operate by means of compressed air. The pump 4 is also of the usual or any suitable type, the barrel 85 being preferably in two parts 5 and 6, with a plunger 7 packed between the barrels.

Both the motive-engine and the pump being of the usual construction and well understood do not require further description.

Compressed air is supplied through the pipe 9, and after acting in the initial or high-pressure cylinder 2 passes through the first exhaust-pipe 10 to a chamber or vessel having two sets of adjacent passages, entering at 12, 95 and is diffused around the tubes 13, rises slowly to the outlet at 14 and from there passes through the pipe 15 to the second or low-pressure cylinder 3, and after acting in that cylinder is exhausted through the pipe 16 into the open air or is conducted to any desirable place. The pump-supply water is drawn through the suction-pipe 17, through the tubes 13, and through the pipe 18, which

latter extends to a sump 19 or to a collecting-reservoir of any kind. The heater 11 is filled with tubes 13, that may be smooth or corrugated, arranged in coils or in any manner 5 that will present a large amount of surface and permit a rapid transfer of heat from the water to the air, or the air can be passed through the tubes 13 and the water flow around them if such an arrangement be 10 deemed better adapted to the conditions of any case.

It will be understood that the heater 11 can be served by either the suction or discharge water of the pump, also that the arrangement 15 of the machinery and apparatus is dependent upon the circumstances of erection and use and is varied accordingly. In general the larger the cooling-surface and the longer the air remains in contact with these surfaces the 20 better the result.

Having thus explained the nature and objects of my invention and the manner of constructing and applying the same, what I claim

as new, and desire to secure by Letters Patent, is—

In combination with the high and low pressure cylinders of a pneumatic engine, a water-pump driven thereby, and a chamber or vessel provided with two sets of adjacent passages, through one set of which passes the 30 water being pumped, the other set being connected on one side with the exhaust of the high-pressure air-cylinder, and on the other side with the inlet of the low-pressure air-cylinder, whereby the temperature of the 35 high-pressure exhaust-air is raised by that of the water being pumped, substantially as specified.

In testimony whereof I have hereunto affixed my signature in the presence of two witnesses.

EDWARD A. RIX.
